UNITED STATES PATENT OFFICE.

ANTON MRAKITSCH, OF DETROIT, MICHIGAN, ASSIGNOR OF ONE-FIFTH TO GEORGE KWETCHER, ONE-FIFTH TO JOHN BINDER, ONE-FIFTH TO VINCENT BRUKLER, AND ONE-FIFTH TO CASPAR WINIGER, OF DETROIT, MICHIGAN.

HORSESHOE.

1,265,942.

Specification of Letters Patent. Patented May 14, 1918.

Application filed March 2, 1917. Serial No. 151,977.

To all whom it may concern:

Be it known that I, ANTON MRAKITSCH, a subject of the Emperor of Austria-Hungary, residing at Detroit, in the county of Wayne and State of Michigan, have invented certain new and useful Improvements in Horseshoes, of which the following is a specification, reference being had therein to the accompanying drawings.

10 This invention relates to horseshoes, and the object of my invention is to obviate the necessity of using horseshoe nails for attaching a horseshoe to a hoof. I attain this object by providing a horseshoe composed of 15 articulated side members and a hoof clip that may be easily and quickly placed in engagement with a hoof and clamped thereon, so that the shoe will be firmly held and cannot be accidentally thrown by a 20 horse. Connected to the side members and other parts of the shoe are novel heel and toe calks, and the shape of the shoe is such that it can be fitted to the average shaped hoof of a horse.

25 My invention will be hereinafter specifically described and then claimed, and reference will now be had to the drawing, wherein—

Figure 1 is a top plan of the horseshoe; 30 Fig. 2 is a rear elevation of the same;

Fig. 3 is a front elevation of the horse- 35 shoe;

Fig. 4 is a longitudinal sectional view of the same; and

Fig. 5 is a cross-sectional view taken on the line V—V of Fig. 1.

The horseshoe comprises curved flat side members 1 having the toe and heel ends thereof provided with openings 2 and the 40 walls of said openings are screwthreaded to receive the threaded stems 3 of toe calks 4 and heel calks 5. These calks are identical in construction and are shaped to engage surfaces and provide sure footing for 45 a horse.

The outer side edges of the members 1 are provided with toe clips 6 and heel clips 7 vertical to the plane of the shoe, these clips being shaped and adapted to be bent over 50 or inclined inwardly, either before or after the shoe is placed in position on the hoof,

to engage the side walls of a hoof and retain the shoe thereon.

Between the toe ends of the members 1 is a toe piece 8 having an upstanding toe 55 clip 9 and lateral apertured lugs 10. The lugs 10 are devoid of screw-threads, as best shown in Fig. 5, so that the threaded stems of the toe calks 4 may extend through the lugs 10 and thus pivotally connect the toe 60 piece to the toe ends of the members 1.

The heel calks 5 have stems thereof extending through flat heads 11 of screw bolts 12 and the apertures of the heads 11 are devoid of screw-threads so that the screw 65 bolts will be pivotally held relative to the heel ends of the members 1. The heads 11 have upstanding flanges 13 at the outer sides of the members 1, and these flanges prevent lateral swinging movement of the bolts 12 70 and relieve the stems of the calks 5 from strains. The screw bolts 12 are connected by a coupling member or nut 14, somewhat similar to a turn buckle, and on the screw bolts are jam or lock-nuts 15 adapted to 75 prevent accidental rotation of the coupling member 14. It is through the medium of this coupling member that the heel ends of the members 1 may be drawn toward each other to clamp the toe and heel clips against 80 the side walls of a hoof.

One embodiment of my invention has been illustrated, but it is to be understood that the structural elements are susceptible to such changes as fall within the scope of the 85 appended claim.

What I claim is:—

In a horseshoe, members provided with integral toe and heel clips and having the toe ends thereof pivotally connected to a 90 toe piece and the heel ends thereof provided with interiorly screw-threaded openings, means for connecting the heel ends of said members, comprising screw bolts having flattened heads provided with openings of a 95 greater diameter than the screw-threaded openings of said members, heel calks having stems extending through the bolt openings and screwed into the openings of said members, upstanding flanges carried by said bolt 100 heads engaging the outer sides of said members and preventing lateral swinging move-

ment of said screw bolts, said flanges relieving the stems of said heel calks of strains due to any spreading action of said members, a nut screwed on said screw bolts adapted for drawing the heel ends of said members toward each other, and jam-nuts on said screw bolts at the ends of said nut.

Copies of this patent may be obtained for five cents each, by addressing the "Commissioner of Patents, Washington, D. C."

In testimony whereof I affix my signature in the presence of two witnesses.

ANTON MRAKITSCH.
